UNITED STATES PATENT OFFICE.

WILLIAM MOSES CHAPMAN, OF HARTFORD CITY, INDIANA.

MAIL-BOX.

1,393,944.

Specification of Letters Patent.

Patented Oct. 18, 1921.

Application filed April 8, 1920. Serial No. 372,210.

To all whom it may concern:

Be it known that I, WILLIAM M. CHAPMAN, a citizen of the United States, residing at Hartford City, in the county of Blackford 5 and State of Indiana, have invented a new and useful Mail-Box, of which the following is a specification.

This invention relates to deposit and collection receptacles, and more particularly 10 to receptacles of this character especially designed for containing mail.

It is the primary object of the invention to provide a receptacle of this character wherein in the body portion is formed of transparent 15 material to permit the contents thereof to be viewed from the exterior, thus eliminating the necessity of opening the container to ascertain whether or not mail has been deposited.

20 A further object of the invention is to provide novel means for securing the cover or top of the receptacle to the body portion thereof, in a manner to prevent unauthorized persons from opening the receptacle.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

35 Referring to the drawing:—

Figure 1 illustrates a perspective view of the receptacle, the same being partly broken away to illustrate the means for securing the split collar and supporting member to 40 the receptacle, and

Fig. 2 illustrates a fragmental detail view of the lateral ears forming a part of the split collar, to illustrate the manner of securing the ends of the split collar together.

45 Referring to the drawing in detail, the reference character 5 designates the body of the receptacle which is formed preferably of glass, the upper end thereof being open to permit articles to be inserted therein, the 50 lower end of the receptacle being shown as curved as at 6 to enhance the appearance of the receptacle.

55 Formed integral with the body 5, adjacent to the upper end thereof is a rib 7, which extends from the outer surfaces of the body and adapted to accommodate corresponding

recessed portions 8 formed in the collar 9, so that when the collar 9 is clamped around the body 5, the rib 7 will prevent movement of the collar 9 longitudinally of the body 5, 60 due to its engagement with the recessed portions 8.

Lateral ears 10 form the ends of the split collar 9, and these ears are apertured to provide means to receive suitable securing bolts 65 for securing the ends of the collar 9 together to clamp the collar to the body 5. Openings are formed in the rear wall of the collar, and these openings are adapted to register with the openings formed in the 70 hinge members 13 which in turn are carried by the cover 14, whereby the cover 14 is secured to the split collar 9.

At the forward edge of the cover 14 is a hasp 15 which co-operates with the staple 16, 75 carried by the front wall of the split collar 9, for receiving a suitable lock by means of which the cover may be locked in its closed position. This cover is also provided with a transverse slot 17 to permit mail, such as 80 letters or the like to be inserted in the receptacle in the usual manner.

Formed integral with the body 5, and disposed substantially intermediate the length thereof, is a rib 18 adapted to be positioned 85 in the recessed portion formed in the securing member 20, which includes spaced arms having right angled ends 21 apertured to receive suitable securing means to permit the receptacle to be secured to a suitable 90 support.

The securing member 20 is formed preferably of strap iron, and has an arm 22 extending upwardly from the front portion thereof, which arm 22 provides means for 95 clamping letters or articles to the receptacle, in the event that the size of the letter or article is such as to prevent the insertion thereof through the slotted portion 17 of the cover.

100 From the foregoing it is obvious that due to the fact that the receptacle is formed of glass, the contents thereof may be readily viewed through the side walls of the receptacle, thus eliminating the necessity of opening the receptacle to ascertain the contents thereof.

Having thus described the invention, what I claim as new is:—

110 In a deposit and collection receptacle, a body portion formed of transparent material and having an inclined upper edge, an

integral rib formed adjacent to the upper edge thereof, a split collar having a recessed portion adapted to receive the integral rib, a cover for the receptacle, said 5 cover having connection with the collar, means to lock the cover to the collar, an integral rib formed intermediate the ends of the body portion, a securing means having a recessed portion to embrace the latter rib, 10 said securing means having right angled

ends to permit the same to be secured to a support, and a supporting arm secured to the securing means.

In testimony that I claim the foregoing as my own, I have hereto affixed my signature 15 in the presence of two witnesses.

WILLIAM MOSES CHAPMAN.
